UNITED STATES PATENT OFFICE

132,874

DESIGN FOR A GAME BOARD OR SIMILAR ARTICLE

Louis J. De Broux, De Pere, Wis.

Application March 13, 1942, Serial No. 106,190

Term of patent 3½ years

To all whom it may concern:

Be it known that I, Louis J. De Broux, a citizen of the United States, residing at De Pere, in the county of Brown and State of Wisconsin, have invented a new, original, and ornamental Design for a Game Board or Similar Article, of which the following is a specification, reference being had to the accompanying drawing, forming part thereof.

I claim:

The ornamental design for a game board or similar article, as shown.

LOUIS J. DE BROUX.
